UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

SIGNALING SYSTEM.

Application filed September 24, 1924. Serial No. 739,628.

This invention relates to signaling systems, and more particularly to signaling systems adapted to be used in connection with railroad private branch exchange telephone 5 circuits and railroad message and despatch circuits.

In railroad message and despatch systems, a plurality of way stations are connected at intervals with the lines and each station is 10 provided with the customary selector and other apparatus. A comparatively high voltage is required for the operation of this apparatus, and heretofore it has been inexpedient to directly associate telephone private 15 branch exchanges with railroad message and despatch systems because of the detrimental effect such high voltage might have upon the equipment at the private branch exchange. Accordingly, it is an object 20 of this invention to associate a telephone private branch exchange with a railroad message and despatch system in such manner as to eliminate any detrimental effect upon the private branch equipment by the 25 high voltage required for the operation of the signaling apparatus. Other and further objects of the invention will be apparent from the following description, when read in connection with the accompanying drawing, in which appear certain embodiments 30 thereof.

Referring to the drawing, Figure 1 represents a single railroad despatch or message circuit terminating at a telephone private branch exchange; Fig. 2 indicates a circuit similar to Fig. 1 but adapted to be used with a plurality of despatch or message circuits.

The equipment shown at the right of the vertical dotted line in each of the figures in 40 the drawing is located at a terminal room from which a line extends to a plurality of way stations. The equipment indicated at the left of said dotted line terminates at the private branch exchange.

In the drawing, in which like numerals 45 designate like equipment throughout, 5 represents a plug of an operator's cord circuit. This plug is adapted to be inserted in a jack 6, the tip and ring conductors of which extend to an outgoing line that may have a 50 plurality of way stations connected therewith, one of which is shown at 7. A connection may be completed from any of the way stations to a subscriber's station over said line and the connected cord circuit in a

well-understood manner. A selector key 8 is positioned at the private branch exchange which is adapted to selectively signal any desired station connected with the outgoing line. 60

In the operation of this system, it will be assumed that a station connected with the line, for instance station 7, desires to call the private branch exchange operator. To do this, a hand generator 9, which is shown as 65 bridged across the line, is operated and causes current to be transmitted over the conductors 10 and 11, through back contacts of relays 12 and 13 and winding of relay 14. The relay 14 is normally bridged across the 70 line conductors at the private branch exchange, and the closing of this circuit causes its operation. The operation of relay 14 closes a circuit through its make contact, from ground, winding of relay 15 to battery, 75 thus causing the energization of relay 15, which in turn closes a circuit from the battery, winding of relay 16, make contact of relay 15 to ground, thereby operating relay 16. The operation of relay 16 closes a locking circuit through its winding and right make contact, from battery, back contact of relay 17 to ground. The operation of relay 16 also closes a circuit through its 80 left contact from ground, through filament 85 of lamp 18 to battery, which causes the illumination of this line lamp. The lighting of lamp 18 indicates to the attendant at the private branch exchange the presence of an incoming call, and in response thereto, the attendant will insert the plug of one of the toll cords associated with the private branch exchange, such as 5, in the jack 6, thereby closing a circuit from battery, sleeve contacts of said plug and jack, winding of relay 90 17 to ground. The closing of this circuit operates relay 17, which in turn deenergizes relay 16 by opening its locking circuit, and extinguishes the line lamp 18. The operation of relay 17 closes a circuit through its 95 make contact from ground, conductor 19, back contact of relay 20, conductor 21, winding of relay 13 to battery, thus causing the operation of the latter relay. Relay 13, upon operating, connects the calling station 100 7 over conductors 10 and 11 with the private branch exchange, and also opens the circuit previously traced, whereby relay 14 105 was operated when this connection is established between the calling way station 7 and 110

- the private branch exchange conversation may be carried on between the two points, and the attendant at the exchange may complete over the cord circuit associated with
- 5 jack 6 any connection desired by the way station.
- If the private branch exchange operator wishes to call a way station on the message circuit, a plug of one of the toll cords is inserted in the jack associated with the line.
- 10 For instance, plug 5 of the cord is inserted in the jack 6, thereby operating relay 17 as formerly indicated, and the operation of this relay will in turn cause the operation of
- 15 relay 13 and connect the line to the private branch exchange. At this time the attendant proceeds to set the selector key 8 for the code corresponding to the code which will operate the selector apparatus at the way station.
- 20 The operation of the key 8 will send the proper code signals over the circuit comprising the conductors 10 and 11 in the usual manner. As soon as key 8 starts to operate, a circuit is closed from
- 25 ground, through a make contact on the selector wheel, winding of relay 20 to battery, thus causing the operation of this relay. The operation of relay 20 closes a circuit through its make contact from ground, make
- 30 contact of relay 17 conductors 19 and 22, through the windings of relays 12 and 23 in parallel, conductor 24 to battery. The closure of this circuit causes the operation of relays 12 and 23. The operation of relay 23
- 35 connects the signalling equipment to the front contacts of the relay 12, and the operation of the latter relay first opens the line toward the private branch exchange, and then connects the high voltage signalling apparatus to the line over conductors 10 and 11. The operation of relay 20 opens the circuit of relay 13, causing it to release and disconnect the line towards the private branch exchange switchboard.
- 40 After the selector key 8 has been set, the operator causes its release in the usual manner so that it returns to its normal position. When the key releases it sends the number of impulses corresponding to the
- 45 position in which the key has been set. Thus when the key is released, its toothed wheel causes the normally open contacts to intermittently close a circuit from ground, conductor 25, winding of relay 26 to battery which intermittently energizes relay 26.
- 50 When relay 26 operates, it connects high voltage battery in one direction through its front contacts and make contacts of relays 23 and 12 to the line conductors 10 and 11.
- 55 When relay 26 releases it connects the high voltage current in the opposite direction through its back contacts and make contacts of relays 23 and 12 to said conductors. This arrangement has the effect of sending a series
- 60 of low-frequency impulses to the line, and

the selector apparatus at the called station corresponding to the code setting of key 8 will be operated in the customary and well understood manner.

Relay 20 is designed to be slow releasing so that it will remain energized during the intermittent pulses which are sent out by the operation of the selector key 8. After the selector key 8 has returned to its normal position, the energizing circuit for relay 20 is automatically opened and this relay is caused to release. The release of relay 20 opens the circuit previously outlined through relays 12 and 23, causing these relays to release. When relay 12 releases, it connects the line to the contacts of relay 13, and this latter relay in turn is operated by the release of relay 20, which through its back contact, connects ground from the back contact of relay 17 to battery through the winding of relay 13.

80 Relays 17 and 13 are maintained operated while plug 5 is inserted in jack 6.

During the period the comparatively high voltage current is connected from the main battery through the contacts of relay 26 to operate the selector apparatus at a way station. The line extending to the private branch exchange will be open at contacts of relays 12 and 13. The opening of this line at these two points protects the equipment at the private branch exchange from any detrimental effects due to high voltage required for the operation of the selector apparatus connected with the line extending to the way stations.

In the modification shown in Fig. 2, in which more than one message circuit is involved, the selector key 8, instead of being permanently associated with a particular circuit, is arranged so that it can, by means of a cord and plug, be connected to any desired circuit. In order to accomplish this, an additional jack 27 is provided so that when the plug 28 which is connected with the selector key 8, is inserted in the jack 27, it connects the terminals of said key with the signalling equipment in a manner similar to that outlined in connection with Fig. 1.

In Fig. 2 the private branch exchange is signalled and the selector apparatus at the way stations is operated as outlined in the description of Fig. 1. In like manner to Fig. 1 the circuit extending to the private branch exchange is opened at the contacts of relays 12 and 13 during the interval of operation of the selector apparatus to protect the equipment at said exchange from comparatively high voltage current.

What is claimed is:

1. A signalling system comprising a private branch exchange, a line circuit terminating thereat, a plurality of way stations associated with the line circuit, means at each way station for signalling the private branch exchange, means at the private

- branch exchange for selectively signaling the way stations, a relay controlled by said last means, and relay means positioned at different points in the line circuit responsive to the operation of said relay for dissociating said private branch exchange from the line circuit at different points thereof during the interval of selective signaling.
2. A signaling system comprising a private branch exchange, a line circuit terminating thereat, a plurality of way stations associated with the line circuit, means at each way station for signaling the private branch exchange, switching means at the private branch exchange, a battery of comparatively high voltage, means for connecting said battery to the line circuit for impressing thereon pulses of current predetermined by the switching means to selectively signal the way stations, a relay actuated by said switching means, and relay means positioned at different points in the line circuit controlled by said relay for disconnecting said private branch exchange from both sides of the line circuit at a plurality of points thereof during the application thereto of the high voltage current.
3. The combination of a telephone private branch exchange and railroad message circuits terminating thereat, a plurality of way stations associated with each message circuit, means at the way stations for signaling the private branch exchange, means at the private branch exchange for selectively signaling the way stations associated with the message circuits, a relay associated with said last mentioned means, and relays positioned at different points in said message circuit and controlled by the last mentioned relay for disconnecting the private branch exchange from the message circuit at a plurality of points during the interval of selective signaling.

In testimony whereof, I have signed my name to this specification this 22nd day of September 1924.

JOHN F. TOOMEY.
